UNITED STATES PATENT OFFICE

CHARLES S. CAMPBELL AND ALFRED E. HUNT, OF NEW HAVEN, CONNECTICUT, AS
SIGNORS, BY MESNE ASSIGNMENTS, TO REMINGTON RAND INC. OF NEW YORK,
N. Y., A CORPORATION OF DELAWARE

RECORD CARD OR LIKE MEMBER FOR INDEXES OR FILES

Application filed October 10, 1921. Serial No. 506,819.

This invention relates to record members for indexes or files and more particularly to that class of the latter in which each of the reference members is overlapped by the succeeding member and projects a short distance beyond the latter so as to disclose a small portion of its surface to enable the indicia thereon to be read without the manipulation of the members.

10 Our invention is particularly applicable to those indexes or files wherein a plurality of such reference members are carried by or upon a suitable support and usually these members are arranged to slide along suitable 15 guides and to be easily detached from the support and replaced thereupon. In indexes of this type there is a limit to the number of reference members which may be secured upon the support at one time and also a limit 20 to the amount of reference material which may be placed upon one of the members. It is, therefore, often desirable to provide each of the reference members with a relatively large area upon which reference material and 25 indicia may be placed.

Our invention, therefore, has for one of its objects the provision of a reference member or card with which the above advantages, among others, are secured.

30 Another object of our invention is to provide a sectional reference member having a section adapted to be attached to a suitable support and a reference-bearing section hinged thereto.

35 A still further object of our invention is to provide a reference member having a plurality of leaves for the reception of the reference indicia.

Still another object of our invention is to 40 provide a reference member comprising a stub section for attachment to a suitable support and a reference-bearing section hinged thereto comprising a book having a plurality of leaves.

45 To these and other ends the invention consists in the novel features and combinations of parts to be hereinafter described and claimed.

In the accompanying drawings:

50 Fig. 1 is a front elevational view of a plu-

rality of reference members of a modified form attached to a suitable support;

Fig. 2 is a sectional view of one of such members along 2—2 of Fig. 1;

Fig. 3 is a view similar to Fig. 2, but showing the leaves of the reference section separated;

Fig. 4 is a side elevational view of a plurality of reference members of slightly modified form in their nested relation;

Fig. 5 is a sectional view of a modified arrangement of the cards.

Fig. 6 is an enlarged sectional view on line 6—6 of Fig. 1.

To illustrate the principles of our invention, we have shown a supporting member of the general type shown in Patent No. 1,048,056, granted December 24, 1912 to Irving Fisher, wherein a suitably mounted guide strip is adapted to be engaged by tongues 65 projecting from the rear of each of the reference members. This longitudinally extending guide strip 23 is provided with free side edges or flanges which may be slightly raised from the body of the strip and below which 70 are adapted to engage the tongues 12 of the reference members designated generally by the numeral 13.

The reference members consist generally of a stub portion at either the upper or the 75 lower end thereof depending upon the position upon which they are placed upon the support and a section for the reception of reference material which is hinged to the stub portion.

The reference members are provided with 80 stub sections 17 having the depending tongues 18 and hinged to which are books 19 comprising a plurality of leaves. As shown, these books are composed of a piece of flexible material, such as paper or the like, folded upon itself to form the two sheets 20 and 21. Preferably the sheets are folded at such a point that the material of one will extend some distance below the other, so that certain reference material upon one of the sheets may always be exposed. The book 19 is hinged to the stub section 17 by means of a strip of cloth or the like 22 pasted to the back of each 85 of said portions. This provides a convenient 90

95 100

and satisfactory hinged connection between the two sections.

It will be obvious that each of the stub sections is received between the tongues and the body of the adjacent stub section, so that a plurality of these reference members may be supported upon a strip 23 similar to the strip 10 in overlapping nested relation. In such position it is seen that the rear sheet 20 of each of the books entirely covers the front sheet 21 of the preceding book, but leaves a small portion of the sheet 20 of the latter book exposed. The edge of the upper sheet 21 of the next to the top book is noted by the dotted line 24 in Fig. 1.

If desired, however, the tongues may be cut out at such a distance from the edge of the stub portion of the reference member that the margins of both of the sheets may be left exposed. Such an arrangement is shown in Figs. 4 and 6. Moreover, it will be obvious that, if desired, a greater number of sheets than the two shown may be provided. In fact the reference book may contain almost any number of sheets desired and still be hinged to the stub section 17 and a plurality of these sections be arranged in overlapping relation upon the support, as shown in Fig. 1.

In either of the arrangements shown in Figs. 1 and 4, it is noted that the edges of no two leaves or cards will coincide and thus the edges of the leaves are presented to the fingers of the user singly and thus may be easily manipulated, as it is never necessary to separate two or more coincident leaves in order to turn one without the other.

Also additional reference material area be secured by simply pasting to the sheets or pages of the book additional slips of paper.

A particularly advantageous feature of the provision of a hinged reference-bearing section in combination with certain forms of attaching means, of which the one shown is an illustration, resides in the fact that two or more of the cards may be superposed and secured upon the holder in this position, thus greatly increasing the reference bearing or posting surface which may be available upon one holder. This is shown more particularly in Fig. 5 wherein two superimposed cards *b* and *c* are filed between an outer card *a* and an inner card *d*, the stubs of the superimposed cards *b* and *c* being nested between the tongues 12 and the stub body of the card *a*, and the stub of the card *d* being nested between the superimposed tongues 12 and the superimposed stub bodies of the cards *b* and *c*.

The superimposed cards *b* and *c* in this arrangement constitute a double-leaved card having a stub portion and tongue of double thickness. It is thus seen that while two posting surfaces (one upon each side of the card) are provided upon each of the two cards *a* and *d*, four posting surfaces are provided by

the two superposed cards *b* and *c* which, however, occupy no more space longitudinally upon the guide 10 than a single card. It is apparent that as the cards are usually nested, as shown in Fig. 1, the number of them and therefore the amount of posting surface available is limited by the length of the holder or guide strip 10. The superposition of the cards as shown in Fig. 5, therefore, results in the multiplication of the posting surface available one one holder.

This superposition is, of course, particularly desirable where the hinged sections are provided as this enables the outer card to be swung over, the user thereby gaining access to the one below.

The cards shown in Figs. 2-4 may also be attached to the guides in superposed position as shown in Figs. 4 and 6 and eight posting surfaces are available, requiring, however, no more longitudinal space upon the holder than is normally occupied by one card with two or four posting surfaces.

If desired, more than two cards may be placed upon the holder in superposed position and the number of posting surfaces thereby increased to any extent practicable in view of the material of which the cards are made.

While we have illustrated and described some preferred forms of our invention, it will be understood that the same is not to be limited to the exact details shown, but is capable of many modifications and variations which lie within the spirit of the invention and within the scope of the appended claims.

What we claim is:

1. In an index or file, a support including a strip having offset edge flanges and a plurality of reference members adapted to be secured on said support, each of said reference members comprising a stub portion having tongues formed from the body thereof to engage said offset edge flanges, and a book section comprising a group of reference-bearing leaves hinged to said stub portion.

2. In an index or file, a reference member comprising a stub section having tongues cut therefrom for attachment to a support, and a group of leaves hinged to said stub section, a plurality of said reference members being adapted to be superposed whereby the tongue of an outer member will extend through the opening left by the tongue of an inner member to engage a support.

3. A plurality of reference members, a support therefor, said members having stub portions adapted to be attached to said support in nested relation, and a group of reference-bearing leaves hinged to each stub portion.

4. In an index or file, a support, a plurality of reference members secured thereto each including a stub section having means at its intermediate portion by which it is attached to the support and nested with an adjacent stub

section and a book section hinged to the stub.

5. In an index or file, a plurality of stub sections each being adapted to be nested with an adjacent one, said stub sections being nested and slidably connected to a support at their intermediate portions, and a book section hinged to each stub section.

10. In an index or file, a guide strip having offset edge flanges, and an index member comprising a stub section having ears cut therefrom at an intermediate portion thereof by which it is slidably mounted on said strip, and a book having a plurality of leaves hinged to said section.

15. In an index or file, a reference member comprising a base portion, a sheet folded intermediate its ends to form a pair of reference-bearing sections, and a hinge strip secured to said sheet adjacent the fold and to a margin of said base portion, said base portion and sheet lying in the same plane in one position.

20. In an index or file, a reference member comprising a base portion, a sheet folded intermediate its ends to form a pair of superposed reference-bearing sections, and means hingedly connecting said sheet to said base portion in edge to edge relation.

25. In an index or file, a reference member comprising a base portion of heavy sheet material, a plurality of superposed reference-bearing sheets, of substantially thin material, and means hingedly connecting said reference-bearing sheets in edge-to-edge relation to said base portion, the aggregate thickness of said sheets approximating that of the base portion.

In witness whereof, we have hereunto set our hands on the 5th day of October, 1921.

40 CHARLES S. CAMPBELL.

CERTIFICATE OF CORRECTION.

Patent No. 1,741,283.

Granted December 31, 1929, to

CHARLES S. CAMPBELL ET AL.

It is hereby certified that error appears in the printed specification of the above numbered patent requiring correction as follows: Page 2, lines 7 and 8, strike out "similar to the strip 10"; line 37, after the word "area" insert the word "may"; lines 68 and 73, for the numeral "10" read "23", and line 76, for "one" first occurrence read "on"; and that the said Letters Patent should be read with these corrections therein that the same may conform to the record of the case in the Patent Office.

Signed and sealed this 4th day of March, A. D. 1930.

(Seal)

M. J. Moore,
Acting Commissioner of Patents.
